OUTBOARD MOTOR ASSEMBLY

Application filed January 16, 1928. Serial No. 247,004.

Our invention relates to outboard motor constructions.

In our present construction we provide an outboard motor readily attachable to standard types of boats and constructed and arranged so that the housing or frame carrying the propeller is relatively broad and flat, being of stream-line construction or substantially so, and rigidly turnable with the propeller and housing and propeller drive whereby this housing provides rudder surfaces to assist in steering when the boat is being steered by the rotating propeller, as is customary, and also provides a turnable rudder by which the boat may be steered when the propeller is motionless as for instance in coasting. In fact, this stream-line frame carrying the propeller and housing the propeller drive-shaft constitutes a rudder for the boat. In installations for the larger boats this housing may be extended rearwardly or otherwise to provide steering surfaces of enlarged area and greater effectiveness.

Yet another object of our invention is to provide an outboard motor construction having a propeller-carrying housing formed with an anti-cavitation plate and formed of stream-line construction both below and above this plate, the upper stream-line surface rising above the water level whereby to permit of high speeds being attained.

One of the objects of our invention is to provide an outboard motor construction which is capable of extremely high speeds and this object is accomplished by forming the propeller unit or that portion of the unit which projects into the water as an enclosing casing of stream line construction to a point above the water level whereby those portions of the casing which are both below and above the water level will offer a minimum resistance in passing through the water and in utilizing this stream line casing as a means for enclosing not only all the operating parts for the propeller but also as a means for enclosing a water circulating passage adapted to carry the cooling water from a point below the normal water level upwardly through the casing to the jacket of the motor; and

further in providing this stream line enclosing casing with a rearwardly extending anti-cavitation plate disposed thereon at a point below the normal water level and adapted to overlie the wake of the casing and particularly the propeller blades to prevent cavitation; and further in utilizing the under portion of this anti-cavitation plate as a water gathering mouth associated with the propeller itself and arranged so that the propeller in rotating will act as a pump to assist in causing water circulation through the water jacket of the engine; and furthermore in conjunction with this water gathering mouth and propeller, we also provide the stream line enclosing casing with a return passage for the cooling water, the port of which is arranged adjacent to the propeller and in front of the same so that the suction of the propeller will draw the water out through the port, thereby assisting the rearwardly disposed gathering mouth in circulating the water; and this stream line casing as thus constructed is made turnable about its substantially vertically disposed axis so that the boat may be positively steered by turning the propeller casing in the desired direction or in constructions such as illustrated wherein the casing is turnable 360 degrees about the vertical axis, for not only steering but also reversing. In certain larger sizes of outboard motors, particularly where the stream line surfaces of the housing extend rearwardly sufficiently far, they will provide steering surfaces of enlarged area and greater effectiveness so that when the propeller is not rotating, as in coasting, these very same stream line surfaces may be utilized as a rudder.

Yet another object of our invention resides in the provision of a stream-line propeller-carrying rudder turnable for steering and carrying a water gathering inlet constructed and arranged to divert a portion of the moving water into the mouth and upwardly through the water circulating system which passes through the water jacket of the engine.

Yet another object of our invention resides in the particular construction and arrangement of this water gathering mouth prefer-

ably at the rear of the path of revolution of the propeller-blades whereby the propeller itself, when rotating, serves automatically to feed the water through the circulating system and wherein, when the propeller is motionless, the movement of the boat through the water and the flow of the water past the stream-line contour of the housing, causes a portion of the water to be diverted by the 10 water gathering mouth and forced through the circulating system. An ancillary object of this feature of our invention resides in the location of this water gathering mouth and particularly its constructional relation 15 to the stream-line sides of the housing whereby such mouth projects laterally beyond the planes of the stream-line so as to be in position to gather water thereinto as the water flows past the propeller housing. Another 20 ancillary object resides in disposing the front face of the gathering mouth at a slight inclination to the front to back plane of the housing whereby to cause the propeller more effectively to force the water into the mouth. 25 Yet another object of our invention resides in the provision of a propeller-carrying housing consisting of a one-piece light metal casting including a propeller-guard, a propeller-shaft bearing, an anti-cavitation plate and a 30 portion extending thereabove to the normal water line, all of such portions being of stream-line contour.

Still another object of our invention resides in the internal construction of the propeller-carrying housing and particularly in the arrangement of the passages therein for the conduction of water through and out of the housing on its way to and from the water jacket of the engine. An ancillary object 40 resides in the disposition of certain of these internal passages and chambers within the housing as containers for a lubricant for the propeller-shaft and bearings.

Yet another object of our invention resides 45 in the manner in which the water for the water circulating system for cooling the engine is conducted from the top portion of the propeller-carrying rudder to the engine by means of a detachable tubular section containing 50 separate water passages adapted detachably to connect with the motor section and the rudder and which tubular section is adapted to enclose the vertically arranged propeller-shaft above the housing.

55 These and other features of our invention will be apparent from a perusal of the following specifications when taken in connection with the accompanying drawings, wherein—

80 Fig. 17 is a detail showing the inclination of the water gathering mouth.

Referring now to the drawings in detail, the motor 2 is shown as provided with a lower integral crank case casting 4 terminating in a plate-like coupling member or casting 6, see Fig. 2, which detachably couples to the upper portion of a tubular section or casing 8 having an upper boss 10 and a lower boss 12 forming guides to receive a supporting 90 collar 14 adapted to be clamped in position around said tubular section 8 by means of opposed pairs of clamping screws 16 and 18. This supporting sleeve 14 has a laterally extending casting 18 provided with a hollow, 95 transverse bearing 20 and two bracket arms 22 and 24 the former being provided with a clamping screw 26 whereby the outboard motor may be fastened upon and supported on the stern board of the boat. The details 100 of construction of this bracket and of the sleeve 8 are not new in the present application. The sleeve 8 is freely turnable in the supporting collar or sleeve 14 so that this sleeve and the motor may be turned about 105 a substantially vertical axis while at the same time the sleeve and motor and propeller-carrying housing hereinafter described, may be tilted about the transverse pivotal axis 20 thereby allowing the lower end of the device 110 freely to move upwardly and rearwardly when the propeller-guard hereinafter described comes in engagement with an obstruction or the like, thereby preventing 115 breakage of the device and at the same time allowing it to rise when going over shoal places.

The motor driven shaft 28 passes through the lower portion of the motor head crank case and casting plate 6 and passes through 120 the tubular sleeve or upper section 8. The lower portion of the tubular sleeve 8 has outwardly flared sides or walls 30 at its lower end which walls, approaching stream-line contour, terminate in a coupling plate 32 125 which plate is provided with bolt receiving openings 34 and 36 and two water conduit openings 38 and 40 for the reception of water pipes 42 and 44 which pipes extend the length 130 of the tubular sleeve 8 and are flared in-

wardly and upwardly at their lower portions. They are preferably formed substantially parallel at their mid-portions and then flare upwardly and outwardly at their outer portions, terminating in openings 46 and 48 in the upper plate or casting 50 which bolts to the bottom portion of the plate or engine casting 6. This casting 6 in turn, is provided with registering apertures 52 and 54 which connect with the openings 46 and 48 to provide a continuous water passage and these apertures 52 and 54 are, in turn, connected with the threaded ends 56 and 58 to the intake and discharge water pipes 60 and 62 on opposite sides of the engine cylinder casting and which water pipes in turn connect with the water jacketed portions of the engine cylinders. All of this is shown in Fig. 2 and Fig. 5 of the drawings.

One of the main features of our present invention resides in the stream-line construction of or substantially stream-line construction of the housing which carries the propeller. In our present invention the entire housing which projects into water is formed of stream-line construction and is arranged to house and enclose not only the propeller-shaft and the lower extension of the motor shaft 28, but in addition, the water circulating means which carries the water from an inlet located below the normal water level upwardly to and through the cooling jackets of the motor and thence preferably downwardly again to a point of discharge beneath the water level, and in addition, this stream-line housing carries the anti-cavitation plate and also carries the means for automatically forcing the water through the water circulating system. In our illustrated and preferred construction, the water line comes about midway between the anti-cavitation plate and the top of the rudder. In other words, we have found that at high speeds, for the satisfactory and complete functioning of our rudder, it is necessary that the stream-line contour extend above the water level a sufficient distance to take care of the various adjustments and other circumstances that arise during operation. We form the propeller housing or frame as a preferably integral casting of relatively light metal, such as aluminum or aluminum alloy. It may be appreciated that instead of providing an integral casing, this casting may be made in sections, but we prefer to form it of an integral casting comprising the lowermost propeller-guard 64, the housing 66 for the transverse propeller-shaft which extends upwardly as at 68 to the anti-cavitation plate 70 and an upper portion 72 extending above the anti-cavitation plate to a point above the water level and which terminates in a coupling plate 74 adapted to connect by means of bolts 76 to the lower coupling plate 32 at the lower portion of the tubular sleeve 8. The bearing or housing 66 encloses

the substantially horizontal or transverse propeller-shaft 78 and this bearing 66 is provided with appropriate internal bearings 80 and 82 in which this shaft 78 is adapted to rotate, the same being driven by means of a bevel gear 84 rigidly mounted thereon and meshing with a bevel gear 86 fastened on the lower end of the vertical shaft 88 of the substantially vertical motor driven shaft. There is a coupling member 90 which couples the upper end of the lower shaft 88 to the lower end of the motor driven shaft 28. The front end of the housing portion 66 is provided with a detachable nose 92 adapted to bolt, as at 94, to the portion 66 and this nose is provided with an opening 96 normally closed by a screw and into which lubricant or grease may be introduced to the interior of the nose which forms a bearing for one end of the propeller shaft 78. This nose 92 is likewise of stream-line construction and forms with the portion 66 a continuous stream-line contour at this point. The propeller 98 is rigidly mounted on the rear end of the propeller-shaft 78 and the walls of this propeller are tapered in stream-line manner to form a continuous stream-line body with the nose 92 and the house portion 66. By reference to the figures of the drawings it will be seen that the entire housing extending from the lowermost point, such as the propeller-guard 64 to a point above the normal water level, is of stream-line contour and by reason of such fact prevents the creation of voids at the rear of the housing as the boat is propelled through the water. This is an important feature of our present invention. In order to permit steering, the motor is provided with a laterally extending rail 100 and with a tiller handle 102 so that when the handle is turned, the motor, together with the sleeve 8 and the connected propeller-carrying housing, will be turned in the corresponding direction. Thus the housing of stream-line contour and design not only carries the propeller but houses the means for driving the propeller from the prime mover, in this instance the motor. It will, of course, be understood that the scope of our invention includes a construction wherein this propeller-carrying housing may be turned by appropriate control means without turning the motor, and it will also be understood that whereas in our present construction the housing may be turned by means of the tiller 102 into two extreme operating positions located 180 degrees apart on the arc of a circle whereby the propeller may either drive the boat forwardly or, when reversed 180 degrees, drive the boat rearwardly, the invention also contemplates constructions wherein the propeller-carrying housing is not completely turnable in a complete circle but is turnable through an arc sufficient for the usual rudder steering movement.

In another aspect, our invention also con-

templates the utilization of the housing as a means for carrying a water circulating means for the water jacket of the motor. The invention also includes an arrangement where-
 5 by this means includes a water gathering mouth or inlet arranged so that during the forward travel of the boat, the gathering mouth is in the path of a moving column of water, which latter is caused to be moved
 10 either directly by the propeller itself or by the forward travel of the boat through the water (and in some of our constructions the rearward travel of the boat through the water) to force the water upwardly to the
 15 water jacket of the engine. The invention also preferably includes the utilization of the housing as an element of the means for causing the return flow of the circulating water after it has passed through the water jacket
 20 of the engine, in which instance we prefer to conduct this discharge by means of the housing, to a point below the water level and in a manner so that irrespective of any opera-
 25 tive position of the housing during steering, or propulsion of the boat forwardly or back-
 30 wardly, the water discharge orifice will constantly function to assist in the circulation of the water through the water jacket.

In another aspect our invention also in-
 30 cludes a cooling system for outboard motors wherein the housing of stream-line contour which extends up to the water level and which carries the propeller, forms an element of the water circulating system for the water
 35 jacket of the motor, and this contemplates the disposition of a water-inlet and discharge opening on this housing and located below the water level, and the inclusion of the ro-
 40 tating propeller carried by the housing as an element in the water circulating system.

Our invention also contemplates the incorporation, as a part of this propeller-car-
 45 rying housing which extends to the water level and is of stream-line construction
 50 throughout its height, of a water gathering mouth disposed with reference to the stream-
 55 line of the housing and including connections to the motor jacket housed by the housing so that during the forward movement of the boat, the water will be forced thereinto and will be caused automatically to pass through the water jacket of the engine and this fea-
 60 ture of our invention includes either the positive forcing of this water through the circu-
 65 lating system by means of the forward travel of the boat causing the water to pass into the water gathering mouth or by causing the propeller itself to force the water into the water gathering mouth.

60 An important feature of our invention re-
 65 sudes in the fact that in any and all positions of the housing, the water-inlet and discharge orifices for the cooling system maintain a constant relation to the housing, being car-
 70 ried thereby, and in particular maintain a

constant relation to the propeller-blades and their path of travel.

In the form of our invention selected for illustration, the housing is provided with in-
 70 ternal partitions to form the tubular, sub-
 75 stantially centrally disposed bearing 100 of circular cross-section in which the tubular sleeve 88 and the lower section 89 of the power driven shaft 16 are mounted. This hollow sleeve 100 forming a part of the parti-
 80 tion walls, extends up to the top of the propeller housing where it terminates and is formed with a peripheral flange 102 and a re-
 85cessed counter-seat 104 within which is seated the coupling member 90 which couples the power shaft 16 with the lower section of the power shaft 89. In addition, the propeller housing is provided with a transversely dis-
 90 posed horizontal partition wall 106 which separates the discharge water chamber 108 from the lubricant containing chamber 110. This lubricant containing chamber sur-
 95 rounds the gears 84 and 86 and also surrounds the propeller-shaft 78. Immediately be-
 100 neath the anti-cavitation plate 70 which is shown as preferably cast integral with the housing, there is provided an internal pas-
 105 sage-way 112 which extends along only one side of the housing and provides a cross over chamber whereby the discharge water from the upper water chamber 108 passes along the side and beneath the anti-cavitation plate 70 and finally discharges into a chamber 110 having an outlet mouth 116 at the rear edge of the housing below the anti-cavitation plate 100 in advance of but close to the path of travel of the propeller-blades.

As shown clearly in Fig. 5 of the drawings, a water gathering mouth 114 is provided with curved surfaces and on its underside and fac-
 105 ing the mouth 116 of the chamber 110 it is provided with an inlet 118 across which are located a series of spaced apart pins 120 which constitute a strainer. By reference now to Figures 3 and 4 of the drawings, it will be seen that this mouth is approximately twice as wide as the width of the water passage-way 122 which is taken on section line 14—14 of Figure 5 of the drawings and it will also be seen that this gathering mouth projects on each side of the stream-line portions 68 and 72 of the propeller housing whereby, during the forward movement of the boat, the water which passes by the stream-line propeller casing will be forced into the gathering mouth 114 and will thence be forced up through the channel 122, thence up through the inlet water chamber 124, thence upwardly through the inlet pipe 42 to the intake pipe 56 leading to the water jacket of the engine. After passing through the water jacket this water will finally be discharged through the discharge pipe 44 within the sleeve 8 thence it will pass into the chamber 108 thence through 120

the cross-over passage 112 and out through the discharge chamber 110 and mouth 116.

By reference to Figure 17 it will be noted that we preferably incline slightly the front 5 wall of the gathering mouth 114 in a direction so that when the propeller-blades revolve, they will more effectively throw or force the water into the mouth. This inclination is, of course, always made with respect to the 10 correct directional rotation of the propeller-blades. This arrangement is particularly useful in traveling through the water at low speeds.

Not only do we utilize the motion of the 15 boat through the water for causing the circulation of the water from a point below the normal water level, but it will also be noticed that in addition, by arranging the outlet mouth 116 of the discharge chamber 110 20 in a direction facing the rear of the boat, we utilize the movement of water past the stream-line housing to assist in sucking the water out of the discharge mouth 116. The location of this discharge mouth 116 below 25 the water level is very important since it permits the rush of the water past the housing surfaces to pull the discharge water from mouth 116. In the present construction, we have preferably arranged this discharge 30 mouth 116 at the rear of the path of travel of the propeller-blades whereby the suction effect of the propeller-blades, as they rotate will, in addition, cause a positive suction at the mouth of the discharge chamber 110 to 35 pull the water through the circulating system. It is apparent that our invention includes the location of this inlet 118, and also the outlet 116 at various points on the rudder to utilize the function of the movement of the 40 rudder through the water for not only sucking the water from the discharge chamber but also in causing the propeller to suck it out. In addition, our invention includes the location of these water inlets and outlets, or either of 45 them at desirable points to utilize not only the force of the water caused by the movement of the boat therethrough in one instance automatically to feed the water through the circulating system, but also wherein the revolution 50 of the propeller-blades is utilized for automatically circulating the water through the water circulating system of the motor. Thus, with respect to one aspect of our invention we utilize the propeller as one element 55 of the water circulating system to assist in the propulsion of water through the system and this may be accomplished by the propeller in various different ways.

It will thus be seen that by the construction 60 and arrangement of our improved stream-line housing, extending as it does, to a point above the water level, and being entirely of stream-line contour throughout its entire height, we have provided a construction which permits 65 of the travel of the boat through the water at

relatively high speeds, since the stream-line contour at the water line together with the presence of the anti-cavitation plate will prevent the formation of voids at the rear of the housing caused by the travel of the housing 70 through the water, and hence will prevent the formation of air pockets at the propeller. In addition, by reason of the stream-line contour of the housing throughout its entire 75 height and especially to a point above the water line, the throwing of spray by means of this housing when the boat is traveling at high speeds, is eliminated.

It will be further appreciated that by having this housing of stream-line contour as hereinbefore described, and utilizing it as a means for carrying the propeller and as a means for housing the propeller driving connections extending upwardly to the motor, a construction is provided wherein this propeller 80 may be turned to various positions during steering, while at the same time forming a stream-line housing to a point above the water line for driving connections of the propeller and motor.

It will also be appreciated that in our present construction wherein the housing itself is of stream-line construction to a point above the water level and wherein it carries the propeller and houses the driving mechanism from the propeller to the motor and wherein this housing is arranged to be turned not only to various positions for steering, but is arranged in the particular instance to be turned 90 completely to extreme reverse positions of adjustment so that the propeller may be utilized for driving the boat forwardly or backwardly, we have provided a very ingenious and highly advantageous arrangement, and this broad aspect of the arrangement includes 95 not only the present construction wherein the housing is turned rigidly with the motor, but also constructions wherein the housing is turned about a substantially vertical axis 100 without turning the motor.

It will also be appreciated by reason of our improved housing construction we are enabled to utilize this stream-line housing which carries the propeller as an element for circulating water from the body of water through which the boat travels, upwardly through the water circulating jacket of the motor, and as hereinbefore pointed out, this construction is capable of various arrangements for either forcing the water upwardly 115 to the jacket by reason of the propulsion of the boat through the water causing a relative travel between the water and the housing carrying the water-inlet for the circulating system or, alternatively by reason of the revolution of the propeller itself, which directly forces water into the water inlet of the circulating system, or as in the present instance, these two means may be combined.

Another advantage of our invention from 120 125 130

its broad aspect resides in the provision of a water discharge orifice incorporated as a part of the water circulating system for the motor, located below the water level and constructed and arranged so that the movement of the boat through the water, causing the travel of the water past the housing, will suck the water from the discharge orifice of the water circulating system. Alternately, our invention contemplates the utilization of the revolutions of the propeller for also accomplishing this same function and in the present instance we prefer to locate the discharge orifice relatively to the travel of the propeller blades themselves, so as to cause a sucking effect which will pull the discharge water from the discharge orifice. Manifestly, the scope of our invention is broad enough to include other arrangements for causing the revolution of the propeller to automatically draw the water through the circulating system. In our present construction we have utilized both of these functions, that is, we have located the discharge orifice on the housing so that the rush of water past the stream-line surfaces of the housing will assist in pulling the water out of the discharge orifice, and we have also located this discharge orifice at the rear of the path of travel of the propeller-blades so that the latter will also pull the water out of the discharge orifice. In this construction one function will aid the other. It will be appreciated that various constructions, arrangements and sizes of this discharge orifice and also of the inlet orifice for the circulating system are contemplated. It will be appreciated that in such constructions, by reason of the mounting of these orifices on the stream line propeller, the forcing and drawing action of the water into and out of the circulating system is at all times operative, and it will be particularly appreciated that in the present instance where this housing is particularly reversible, so that the propeller carried thereby may propel the boat forwardly or backwardly, the inlet or discharge orifices, or either of them, will be in constant position, irrespective of these or other operative positions of the housing and the propeller carried thereby to draw the water into and out of the circulating system.

The disposition of the outlet or discharge mouth of the water cooling system with relation to the propeller is not confined to the rear or suction side of the propeller since the same might also be locatable at the water forcing side of the propeller providing the discharge outlet faces in the direction of the flow of the water. So also this discharge orifice might be placed some distance in front of the propeller on the housing in the so called sheet stream or flow of the water past the housing, and in this instance it would also be facing toward the rear of the propeller.

It will also be appreciated by reason of the internal construction of my improved housing, and particularly with reference to the stream-line contour thereof and its extension to a point above the water line, we are enabled to utilize this turnable housing as a means for housing the water connections to the motor jacket, while at the same time permit high speeds of travel of the boat through the water. We are also enabled to provide a very advantageous assembly not only of the housing in shiftable operative position, but also of connections from the housing to its shifting and supporting means and also with relation to the substantially vertically disposed motor, drive shaft passing therethrough and housed thereby and the connections to the propeller-shaft proper, housed and mounted on the housing. In addition, the internal arrangement of this housing provides a chamber or chambers for the housing of lubricant for the propeller driving mechanism and the provision of stream-line openings through the housing surface into which this lubricant may be inserted.

In addition, another advantage of our present construction resides in the construction of the housing as a practically integral casting including the housing guard, the bearing for the transverse propeller-shaft and the structure thereabove extending to the water line and including the anti-cavitation plate, all of stream-line contour, and this casting is easily assembled by the utilization of a nose cap, and the propeller, which are connectable to the casting and when so connected, complete the stream-line contour. It must be appreciated that this casting may be formed with the nose cap integral with the casting, but in the present construction we prefer to form the nose cap separately for ease in assembly.

Still a further feature of our advantage resides in the provision of an upper tubular section or sleeve adapted to be bolted to the top of the stream-line housing and which upper section at its bottom is of stream-line contour or approaches a stream-line contour, and this upper section is highly advantageous in facilitating ease in assembly and it is further featured by the fact that it is provided with the separate inlet and outlet pipes connecting the housing water compartments with registering water openings in the base of the crank case.

Still a further advantage of our improved construction resides in the details of construction of the anti-cavitation plate, which is preferably formed hollow, so as to provide not only a cross-over passage for the conduction of the discharge water, but also to provide an integral water gathering mouth at its rear adapted to deflect the water into the inlet of the circulating system; and a further advantage of this inlet mouth resides in its

relatively wide dimension and arrangement at the rear of the stream-line sides of the housing and projecting laterally outwardly therefrom. A further feature resides in the 5 details of arrangements of this gathering mouth with respect to the oppositely disposed water discharge mouth located at the rear and between which the propeller-blades travel to accomplish the functions herein- 10 before described.

Having thus described our invention what we claim as new and desire to secure by Letters Patent is:

1. In an outboard motor construction, the 15 combination of a motor having a water jacket, a housing carrying a propeller and means enclosed by the housing for driving the propeller from the motor, said housing extending upwardly to the water level and 20 being of stream line construction; and water circulating means for conducting water from a point below the water level upwardly to the water jacket of the engine by means including a passageway housed by the housing, 25 said passageway terminating in a water gathering mouth located at the rear of the housing and of sufficient width to extend outwardly laterally thereof beyond the outermost plane of the stream line side surfaces 30 of the housing.

2. In an outboard motor assembly, the combination of a motor having a substantially vertically depending drive shaft and a tubular sleeve surrounding said drive shaft, a 35 housing rigidly mounted on said tubular shaft, said housing including a propeller guard, a substantially cylindrical bearing for the propeller shaft and having a portion extending upwardly to a point above the normal water 40 level said latter portion extending upwardly including an integral and rearwardly extending anti-cavitation plate, said upwardly extending portion being of stream line construction to a point above the normal water 45 level.

3. In an outboard motor assembly, the combination of a motor and a housing, said housing carrying a propeller, said housing extending upwardly to the water level and being 50 of stream line construction throughout its height, the said housing including an anti-cavitation plate overlying the path of travel of the propeller; said anti-cavitation plate 55 having a passageway formed therein and terminating in a water gathering mouth extending laterally outwardly on opposite sides of the stream line side walls of the housing, whereby it projects beyond the planes of said 60 side walls, the width of said gathering mouth being substantially twice the width of the passageway in said anti-cavitation plate, and a passageway formed through said housing and connecting with the passageway formed 65 in the anti-cavitation plate at one end and

connecting to the water jacket of the engine at the other end.

4. In an outboard motor, the combination of a water jacketed motor, a housing of light weight metal and including as an integral casting, a propeller guard, a propeller shaft bearing, and an upper portion extending above the water level and provided with an integral laterally extending anti-cavitation plate, said casting being of stream line contour throughout its height, said anti-cavitation plate having a hollow portion provided with a water gathering mouth and said casting being provided with a conduit connecting said mouth with the water jacket of the 70 motor. 75

5. In an outboard motor assembly, the combination of a water jacket, a motor and a housing, said housing carrying a propeller, said housing extending upwardly above the water level and being of stream line construction throughout its height, said housing having a centrally disposed vertically extending sleeve therethrough and lateral partitions dividing the housing into a water-inlet passage-way and a water discharge passage, an anti-cavitation plate extending rearwardly of the housing and terminating in a water gathering nozzle connected to the inlet passage, said anti-cavitation plate forming a discharge 80 85 90

chamber terminating in a mouth disposed in spaced relation from the gathering mouth, said discharge orifice and gathering mouth being located on opposite sides of the path of travel of the propeller blades, a cross over 95 100 passage formed interiorly on the under side of said anti-cavitation plate and connecting the water discharge chamber on one side of the centrally disposed hollow sleeve with the water discharge chamber on the other side thereof, and water conduits connecting the inlet of discharge chambers in the housing to the inlet and discharge chambers of the water jacket of the motor, and a drive shaft connected to the motor and to the propeller, said drive shaft passing through a centrally disposed tubular sleeve formed in the housing. 105 110

6. In a device of the class described, the combination of a water jacketed motor and a housing, said housing extending to a point above the water level and being of stream line construction throughout its height, said housing carrying a propeller, and said housing being formed with inlet and water discharge terminating in orifices disposed below the normal water level, and an upper tubular section detachably bolted to the upper portion of the housing, the lower portion of said section being substantially of stream line construction, said upper section having its top detachably connected to the motor, said section having mounted therein water pipes connecting with the passages in the housing and with the passages in the motor. 115 120 125

7. In a water propulsion device, the com- 130

bination of a support, a propeller thereon, said support carrying a water-inlet connected to the water jacket of the engine and located at the rear of the path of travel of the propeller-blades, said inlet being inclined so that one lateral edge is closer to the path of travel of the propeller blades than the other, said inclination being in a direction to assist the water forced rearwardly by the propeller 10 to enter the inlet.

8. In an outboard motor construction, the combination with a stationary support having a stream like bearing, a substantially vertically depending hollow sleeve mounted for 15 turning in said bearing, an explosion motor mounted on the upper end of said support and having its crank shaft concentric with the axis of the turnable tubular sleeve, a drive shaft extension for said crank shaft passing 20 downwardly through said tubular sleeve, a housing rigidly mounted at the lower portion of said tubular sleeve, said housing enclosing the lower portion of said vertically extending drive extension shaft and enclosing a propeller shaft disposed at right angles to said drive 25 shaft and enclosing driving connections between said shafts, a propeller mounted on the end of said propeller shaft, said housing extending from its propeller shaft portion upwardly to a point above the normal water 30 level and being of stream line construction throughout such extension and said housing having a relatively thin anti-cavitation plate cast integral therewith and located at a point 35 below the norml water level at a point such that it extends over the path of travel of the propeller blades, and said housing having two vertically extending internal passages, each opening below the normal water level 40 and each connecting to water conducted means passing upwardly through the hollow sleeve, and means connecting each of the passages in said hollow sleeve with the water jacket of the engine.

45 9. An outboard motor construction comprising a sleeve like support, a tubular sleeve turnably mounted therein, an explosion motor mounted on the upper end of said tubular sleeve and having a drive shaft passing 50 through said tubular sleeve and depending substantially vertically, a vertically extending metal housing rigidly connected to the lower portion of said tubular sleeve and enclosing the lower portion of the vertically depending engine drive shaft, the lower portion 55 of said housing having a horizontally disposed barrel like portion, a horizontal drive shaft mounted in said barrel like portion, and geared connections between said 60 horizontal shaft and said vertically depending drive shaft enclosed in said housing, a propeller on the end of said horizontal shaft, said housing carrying a rearwardly and laterally extending anti-cavitation plate over- 65 lying the path of travel of the propeller blades

and said housing being of stream line construction from the barrel shaped portion upwardly to a point above the normal water level and said housing being provided with two spaced apart internal water passages extending vertically upwardly therethrough, the lower portions of said passages opening below the normal water level of said housing, and means forming two spaced apart water conduits extending longitudinally upwardly 70 through said tubular sleeve on opposite sides of the vertically depending drive shaft mounted therein, said passages communicating respectively with the passages in the housing and with the water jacket of the engine whereby when the housing is moved through the water, it may be freely turned for steering while at the same time permitting water to flow from the body of the water in which the housing is submerged upwardly 75 through said housing and through said tubular sleeve to the water jacket of the engine and thence down through said tubular sleeve and said tubular housing, backwardly into the body of water in which the housing is submerged.

10. In an outboard motor construction, the combination of a motor having a water jacket and vertically depending drive shaft, a tubular sleeve concentrically surrounding said drive shaft, said tubular sleeve being formed on its lower portion with a flange, a housing of stream line formation, said housing being provided on its upper portion with bolt openings, bolts passing through openings in the flange on the tubular sleeve and into the openings in the upper portion of said housing whereby to secure said housing to the lower portion of said tubular sleeve and said drive shaft passing through said tubular sleeve and into the lower portion of said housing, a propeller shaft carried by the lower portion of said housing, a propeller on said shaft and gearing connections housed in said housing and connecting the drive shaft and the propeller shaft.

11. In combination in a device of the character described; a submersible housing element provided with an anti-cavitation plate intermediate its top and bottom, a bearing partition dividing said element transversely into forward and rearward chambers; and a second housing element provided with a cap member secured to said first element to close said chambers and conduits extending therethrough in communication with respective chambers.

In witness whereof, we have hereunder subscribed our names.

LOUIS J. JOHNSON.
